BASEBALL PLAYER'S MITT OR GLOVE

Filed Oct. 31, 1925

U. C. Berry INVENTOR.

BY Emil F Lange
ATTORNEY.

UNITED STATES PATENT OFFICE

UPTON C. BERRY, OF LINCOLN, NEBRASKA

BASEBALL PLAYER'S MITT OR GLOVE

Application filed October 31, 1925. Serial No. 65,996.

My invention relates to base ball mitts or gloves, its object being the provision of a glove or mitt which with slight variations may be used by the various players of a base ball nine, which is so constructed that it will adapt itself to all hands from the largest to the smallest, which will cushion the ball more effectively than other gloves will, and which possesses various novel features of construction which will be fully set forth in the following description. Having in view this object and others which will be mentioned in the following description, I will now refer to the drawings, in which Figure 1 is a view of the palm surface of the mitt.

Figure 1^a is a similar view of the palm surface but in reduced size and showing the action of the ball against the flange.

Figure 2 is a view of the back surface of the mitt.

Figure 2^a is a similar view in reduced size but showing a slight modification.

Figure 3 is an edge view of the mitt drawn to a reduced scale.

Figure 4 is a view of a portion of the interior of the mitt, the mitt being sectioned a short distance back of the hand opening.

Figure 5 is a sectional view, the section being lengthwise of the mitt.

Figure 6 is another sectional view of the mitt and showing particularly the arrangement of the finger stalls and the attachment for reducing the size of the wrist opening.

Figure 7 is a perspective view of the interior of the mitt.

Figure 8 is another perspective view of the interior of the mitt showing particularly the position of the hand with relation to the finger stalls.

Figure 9 is a view in perspective of the roll padding, the figure being drawn to a reduced scale.

The mitt proper includes a back portion 10 of leather, cloth or leather lining 10^a, and a palm 11. The parts 10 and 10^a are secured together preferably by several lines of stitching at the wrist portion and they are secured together and to the palm 11 by rivet eyelets along the outer edges. While these

parts are preferably secured together by means of rivet eyelets, they may be stitched together at all of their edges, and in practice it is desirable that they be stitched together at the junction of the thumb and body portions of the mitt so as to avoid injury to the ball. Strips 12 of flexible material are sewed at their ends to the parts 10^a and 11 to form finger stalls for the player. Additional strips 13 in looped form are secured to the parts 10 and 11 at the edges. The strips 13 thus form loops for engaging the thumb and little finger of the player and for thus keeping the hand spread and in comfortable position, the other fingers resting in the finger stalls between the strips 12. The opening between the back and the palm of the mitt is made large enough for the introduction of the hand and because of the general shape of the mitt the opening will in most cases be found to be of the most comfortable size for the wrist. In case, however, it is desired to restrict the size of the opening, a strip of padding 14 may be attached to the parts 10 and 10^a by means of snap fasteners as shown in Figure 4. The strip 14 may be inserted or removed whenever desired. A similar result in permanent form may be secured by attaching a strip of padding 14^a to the edges of the back portion as shown in Figure 2. The back portion may be further modified as in Figure 2^a by cutting away a portion 15 to relieve the pressure on the player's knuckles. The opening 15 may be made in the part 10 only or in both the parts 10 and 10^a. In either case the parts 10 and 10^a are stitched together at the edges of the opening. The padding of the mitt includes two layers 16 of wool felt and a roll 17 of hair felt, all of the layers being firmly stitched together to prevent any possibility of displacement. The layers 16 cover the entire palm of the mitt and are arched. The false palm 19 and the outer felt layer 16 are arched inwardly and are bound by the edge padding or roll 17, while the palm 11 and the inner layer of felt 16 are also arched but to a greater extent; thus forming a space 18 between the two arched portions of the glove. The space 18 provides an air

5 pocket which can not be completely crushed or collapsed. The spreading of the glove by the hand opens the air space 18 after impact of the ball in the palm of the glove. Both the wool felt padding and the hair padding possess considerable resiliency, but not sufficient to cause the ball to bounce. The air pockets 18 form air cups for cushioning the impacts of the ball. Under the pressure of 10 the ball the air or a portion of the air is forced out through the padding, but owing to the resiliency of the material the air is drawn back into the pockets as the pressure is released.

15 The false palm 19 is laced to the mitt proper, it being provided with rivet eyelets at its edges. The palm 11 has rivet eyelets at the wrist portion as shown in Figure 2 while the rivet eyelets secure the parts 10, 20 10^a, and 11 together at all other edges. Owing to the roll padding 17 the ball pocket of the mitt is relatively one and one-half times the diameter of the ball. This depth may, however, be varied considerably by increasing or decreasing the thickness of the 25 roll padding 17. When the ball strikes the side of the pocket the depth of the pocket usually prevents the ball from bouncing out of the mitt. This is of great importance particularly to amateur players, who are apt 30 to lose the ball. The ball can be made still further secure by means of a horse-shoe shape strip 20 of leather which is stitched at its outer edge only to the false palm 19. The effect of the ball on this strip 20 is shown 35 in Figure 1^a. As the ball glances out of the pocket it strikes the loose edge of the strip 20 and is thus easily held in the pocket.

40 The parts 10 and 10^a of the glove are practically integral since they are united by the stitching or by means of rivet eyelets, or both. The stitching may be confined to the edges or if preferred, there may be numerous lines of stitching across all 45 parts of the back. The palm 11 is secured to the parts 10 and 10^a by means of rivet eyelets along all parts of the edge except at the hand opening. During use of the glove and while inserting the hand into the 50 glove or removing it therefrom, there is considerable strain at the edges of the hand opening and this strain would ordinarily tend to pull out the eyelets at the junctions. In order to prevent this there are two pairs 55 of additional eyelets, one pair at each side of the opening as shown in Figure 2 and Figure 2^a, and through these eyelets are passed thongs 21. The eyelets through which the thongs 21 pass are disposed at each end of the hand receiving opening, and one of each passes through the back 10 adjacent the opening while the other eyelet is spaced away from the opening and preferably passes both through the back 10 and palm 11. The palm 11 also has an eyelet

near the opening which registers with the eyelet carried in the back only. The thongs 21 thus bind the back 10 and palm 11 together at the opposite ends of the hand receiving opening. These thongs thus receive 70 all of the strain and prevent injury to those parts of the glove adjacent the hand opening. Additional pairs of rivet eyelets are secured through the portions 10 and 10^a at the outer ends of the thumb portion and the 75 body portion. These eyelets are connected by thongs 22, the purpose of this arrangement being to make that part of the palm adjustable to the convenience of the player. There is also provided a scuff strip 23 at the 80 edge of that part of the glove occupied by the little finger. Moving balls are frequently scooped up from the ground and the scuff strip 23 being placed at the point of greatest wear, will reinforce the glove 85 and considerably increase its life. The repeated impacts of the ball tend to weaken the leather of the false palm 19 especially about the thumb portion. For reinforcing this portion, a strip of leather 24, shown in 90 dotted lines in Figure 1, is secured along the margin of the part 19, through the thumb and little finger portions, and it may be extended around the entire edge of the part 19, but its main importance is at the 95 junction of the thumb and body portions to prevent the ball from loosening the eyelets at that point. The padding 14 may be secured to the parts 10 and 10^a by stitching, or it may be secured so as to be more readily 100 detachable, as by means of eyelets and thongs similar to those shown at 21, or by means of snap fasteners or the like.

Having thus described my invention in such full, clear, and exact terms that its 105 utility will be readily understood by others skilled in the art to which it pertains, what I claim as new and desire to secure by Letters Patent of the United States is:

110 A base ball player's mitt or glove including back and palm portions for receiving a player's hand therebetween, a padded false palm secured at its edges to said back and palm portions, and a horse-shoe shaped strip of flexible material secured at its outer 115 edge only to said false palm against the outer surface thereof.

In testimony whereof I affix my signature.
UPTON C. BERRY.
